[57] CLAIM

The ornamental design for a chair body, as shown and described.

DESCRIPTION

FIG. 1 is a top, left perspective view of a chair body embodying my new design;

FIG. 2 is a top plan view thereof;

FIG. 3 is a left side elevational view thereof, which is a mirror image of the right side elevational view thereof;

FIG. 4 is a front elevational view thereof;

FIG. 5 is a rear elevational view thereof; and,

FIG. 6 is a bottom plan view thereof.

The broken lines depicting the chair leg structure in FIG. 1 are included for illustrative purposes only and form no part of the claimed design.
